UNITED STATES PATENT OFFICE.

BENJAMIN KEEN, OF BRIGHTON BEACH, NEW YORK.

CARD CASE.

Application filed October 18, 1927. Serial No. 226,992.

This invention relates to card cases. One object of the invention is to provide an improved case of light construction for holding cards, or the like thin, flat articles in neat, compact relation, and permitting a card to be partially ejected in a convenient and expeditious manner by the use of only one hand, for ready withdrawal by the recipient of the card.

10 A further object of this invention is to provide an improved card case of the character described, having a holder which can easily be opened for loading with cards, or similar devices, and in which the ejecting means has novel coaction with the holder and is so constructed as to eliminate any possibility of injury to the cards.

15 A further object of this invention is to provide an improved card case of the character set forth having few and simple parts, which shall be comparatively inexpensive to manufacture, and withal durable, and efficient in use to a high degree.

Other objects of this invention will in 20 part be obvious and in part hereinafter pointed out.

The invention accordingly consists of the features of construction, combinations of elements, and arrangement of parts which 25 will be exemplified in the construction hereinafter described, and of which the scope of application will be indicated in the following claim.

In the accompanying drawing, in which 30 is shown one of the various possible illustrative embodiments of this invention,

Fig. 1 is a perspective view of a card case embodying the invention, showing the device in the step of ejecting a card.

40 Fig. 2 is a transverse sectional view of the card case, taken on line 2—2 of Fig. 3.

Fig. 3 is a longitudinal sectional view of the card case, taken on line 3—3 of Fig. 2.

45 Fig. 4 is a perspective view of the holder portion of the card case.

Fig. 5 is a detail perspective view of the follower plate carried by said holder, adapted normally to urge a card into the path of the ejector.

50 Fig. 6 is a perspective view of the ejector plate.

Fig. 7 is an enlarged fragmentary sectional view of one end of the card case, as seen from line 7—7 of Fig. 1.

55 Fig. 8 is a transverse sectional view, sim-

ilar to Fig. 2, of a modified form of casing and ejector.

Referring in detail to the drawings, the card case C embodying the invention may be made of any suitable material as, for example, light metal. Said card case comprises a casing 10 in which is positioned a holder 11 adapted to receive a plurality of cards 12, or similar flat articles. Holder 11 is provided with a follower 14 to normally urge a card into the path of an ejector 13, slidably supported on casing 10 in a manner hereinafter appearing.

The holder 11 is shaped to receive the cards 12 snugly, and is preferably of the form of a box section, stamped from a single sheet of material to provide a bottom wall 15, side walls 16, and end walls 17, 18. The front end wall 17 has a notch 19, of sufficient depth to permit a card to be moved outward from the holder 11, when ejector 13 is actuated. The rear end wall 18 is formed with notches 20, 21, for a purpose hereinafter appearing.

The casing 10 may likewise be stamped from a single sheet of material and includes a top wall 22 and depending side walls 23 having inwardly extending flanges 24 to engage the bottom of the holder 11. Said casing 10 is open at one end 25 thereof to freely receive the holder 11 therethrough, while the other end is closed by a wall 26. Any suitable means is provided on the casing to act as a stop for the holder so that the end walls 18 and 26 will be spaced apart, for a purpose hereinafter disclosed, said means herein taking the form of prongs 27 struck downward from the top wall 22 of the casing, in proximity to the wall 26 thereof, and spaced therefrom.

95 The ejector 13 consists of a flat plate 28 of a width approximately equal to that of casing 10, said plate being recessed at 29 to provide a projection 30 having a foot 31 depending at an angle from said plate. A head or finger piece secured to said plate comprises a stud 32, riveted to said plate, or, in some other well-known manner, secured thereto, a button 32^a being formed on the end of said stud. Said stud is slidably received in a longitudinal slot 33 in the top wall 22 of the casing 10. Removal of the ejector from said casing is prevented by the coaction of button 32^a with wall 22, the edge portions 34 of said plate slidably engaging 100

110

the side walls of the card case to be guided thereby.

The follower 14 has depending guide flanges 35 at the ends thereof to contact the walls 17, 18, of the holder 11 to permit easy sliding movement of the follower when acted upon by the springs 36. The latter may be helical in form, and are secured to said follower in any suitable manner, herein 10 showed as fixed thereto by means of pins 37. The springs are thus free to rest on the bottom wall 15 of the holder, urging the follower 14 upward to move cards 12 supported on said follower into the path of the foot 31 15 of the ejector.

After the follower 14 has been positioned in holder 11, cards 12 are placed in said holder, the follower being simultaneously depressed. Then, ejector 13 having been 20 moved to the rearmost position in casing 10, in which position the depending foot 31 will be positioned in abutment with wall 26 of the casing and behind prongs 27, the holder 11 is inserted in casing 10, with wall 25 18 entering first. The holder is then pushed into said casing as far as it will go, when the wall portions at slots 21 will contact the prongs 27, while front wall 17 will be positioned to present a closed front wall for 30 the card case C. If it is now desired to dispense a card 12, ejector 13 is slid forwardly of casing 10 by manipulating button 32. Side edge portions 34 of plate 28 will coact with the walls 23 of casing 10 to guide said 35 plate, foot 31 passing through slot 20 and engaging the rear edge of a card 12. Continued movement of button 32 will cause the ejection of a card at opening 19 from holder 11.

In cases where ejector plate 28 is made 40 the width of a card, the edge portions 34 are guided in the holder 11, being received in contact with walls 16 of said holder. Slots 21, in such case, permit the complete rearward movement of said plate, being 45 slightly greater in depth than the thickness of plate 28. By this latter construction, a relatively tight fit between walls 16 of holder 11 and the top wall 22 and flanges 24 of casing 10 is realized.

50 In Fig. 8 is illustrated a further method for guiding ejector 113 in the casing 110. In this construction, the top wall 122 of casing 110 is stamped to form the groove 39 paralleling slot 133. Ejector 113 is made 55 of sufficient width to snugly fit in groove 39, and to be guided thereby. The depth of said groove is slightly greater than the thickness of the plate 128 of said ejector, thereby completely housing the same, a foot 60 131 extending from said plate to a point below the bottom face of wall 122 in order to contact with cards 12 received in holder

111. Holder 111 is provided with a slot 120 to accommodate said foot 131, while casing 110 may be provided with prongs similar to 65 prongs 27 of casing 10.

If desired, foot 31 may be sharpened to a fine edge at its end, presenting a flat surface contacting the wall 26 of the casing 10, and a bevelled sloping edge, rising toward the 70 front of the casing. By this means, it is possible to eliminate the necessity for such spacing means as the prongs 27.

It can readily be seen that because of the 75 simple construction, the case may conveniently be held in the palm of the hand and button 32 actuated by the thumb of the same hand to eject a card.

As ejector 13 is moved back to its initial 80 position in casing 10, after a card 12 has been withdrawn therefrom, foot 31 will ride over the face of the next card to be discharged. To avoid scratching or marring said card, foot 31 may be given a relatively large width to reduce the frictional 85 pressure on said card per unit of width, or the edge of the foot may be recessed centrally as at 38 to avoid any contact with the card at points where the latter carries printed matter.

90 It will thus be seen that there is provided a device in which the several objects of this invention are achieved, and which is well adapted to meet the conditions of practical use.

95 As various possible embodiments might be made of the above invention, and as various changes might be made in the embodiment above set forth, it is to be understood that all matter herein set forth or shown in the 100 accompanying drawing is to be interpreted as illustrative and not in a limiting sense.

Having thus described my invention I 105 claim as new and desire to secure by Letters Patent:

In a card case, a holder for cards, a casing for said holder, an ejector comprising a plate having a foot at the rear edge thereof, said casing having an externally raised portion in one wall thereof forming a guiding groove for said ejector plate in the interior surface of said wall, said groove being deep enough to house said ejector plate out of contact with the face of a card and 110 long enough to permit the foot of the ejector to engage the rear edge of a card, said groove having a slot, a finger piece extending through said slot for operating said ejector, and a follower in said holder for 115 forcing a card into the path of said ejector.

120 In testimony whereof I affix my signature.

BENJAMIN KEEN.
